CHILD'S SPOON OR SIMILAR ARTICLE

Helen R. Chinnock, New York, N. Y.

Application October 1, 1948, Serial No. 148,910

Term of patent 14 years

(Cl. D44—29)

To all whom it may concern:

Be it known that I, Helen R. Chinnock, a citizen of the United States, residing in New York, in the county of New York and State of New York, have invented a new, original, and ornamental Design for a Child's Spoon or Similar Article, of which the following is a specification, reference being had to the accompanying drawing forming a part thereof.

Fig. 1 is a top plan view, showing my new design of a child's spoon or similar article;

Fig. 2 is a side view of my new design;

Fig. 3 is a perspective view of the side of the spoon tilted at an angle from the top plan view in Fig. 1; and

Fig. 4 is an end view of my new design looking from the back forward of Fig. 2.

I claim:

The ornamental design for a child's spoon or similar article, as shown.

HELEN R. CHINNOCK.
